UNITED STATES PATENT OFFICE.

ROMANOS S. SIMHAN, OF BIRMINGHAM, ALABAMA.

DEVICE FOR HOLDING SHEET-MUSIC.

1,195,110.

Specification of Letters Patent. Patented Aug. 15, 1916.

Application filed December 8, 1915. Serial No. 65,791.

To all whom it may concern:

Be it known that I, ROMANOS S. SIMHAN, a citizen of the United States, residing at Birmingham, in the county of Jefferson and State of Alabama, have invented new and useful Improvements in Devices for Holding Sheet-Music, of which the following is a specification.

This invention relates to improvements in devices for holding sheet music and has particular application to a device for holding sheet music upon a piano or analogous musical instrument.

In carrying out the present invention, it is my purpose to provide a device of the class described whereby the sheet music may be held upon the piano or similar instrument within convenient reach of the performer and in such manner as to eliminate the accidental turning of the music sheet or the displacement of the composition from the instrument.

It is also my purpose to provide a holder for sheet music which will embrace the desired features of simplicity, efficiency and durability, which may be manufactured and marketed at small cost and which will hold the sheet music securely in place upon the instrument being played.

With the above and other objects in view, the invention consists in the construction, combination and arrangement of parts hereinafter set forth in and falling within the scope of the claim.

In the accompanying drawings; Figure 1 is a fragmentary side elevation of a piano showing my improved sheet music holder in place thereon. Fig. 2 is a front elevation of the same, the sheet holder being shown in open position. Fig. 3 is a longitudinal sectional view through the supporting means for the sheet holder. Fig. 4 is a sectional view through the sheet holder. Fig. 5 is a similar view taken at right angles to Fig. 4.

Referring now to the drawings in detail, 1 designates an upright piano or similar musical instrument. Arranged across the top of the piano 1 is a supporting rod 2 comprising outer and inner telescoping sections 3 and 4 respectively. The outer end of the section 4 is downturned as at 5 and equipped with a clamping screw 6, while secured to the outer end of the section 3 and depending therefrom is a clamping lug 7 equipped with a clamping screw 8. The inner end portion of the section 3 carries a set screw 9 adapted

to engage the adjacent portion of the inner section 4 to hold the sections 3 and 4 in adjusted relation. When the supporting rod 2 is arranged across the top of the piano the downturned end 5 engages the back of the piano while the clamping lug 8 engages the front of the piano. The sections 2 and 4 are drawn together in order to hold the end 5 and the lug 7 in engagement with the respective walls of the piano and the set screw 9 turns to lock the sections together. After this adjustment of the sections, the clamping screws 6 and 8 are clamped against the adjacent walls of the piano to hold the supporting rod securely upon the piano.

Pivoted to the outer end of the section 3 by means of a combination pivot and lock joint is a supporting rod 10 comprising outer and inner telescoping sections 11 and 12 respectively, the outer section 11 being pivoted to the section 3 of the rod 2. Pivoted to the outer end of the section 12 of the rod 10 by means of a combination pivot and lock joint is a supporting arm 13 formed of telescoping sections 14 and 15. The sections of the rod 10 and the arm 13 are adapted to be locked in the desired adjusted position by any suitable means, as by the set screws illustrated in the drawings.

16 designates a sheet holder comprising outer cover sections 17 and 18 arranged edge to edge and having the meeting edges thereof pivoted to each other by means of the rod 13 so that the sections may be swung to open and closed positions independently of each other. Arranged upon the inner surfaces of the outer sections 17 and 18 are substantially rectangular frames 19, 19 respectively having the outer side edges thereof hinged in some suitable manner to the corresponding edges of the respective sections, while hinged to the inner edge of the frame 19 connected to the outer section 17 is a frame 20 capable of swinging movement between the cover sections and placed upon the frame 20 in face to face contact therewith is a frame 21 having the outer edge thereof hinged by any suitable means to the corresponding edge of the frame 20. In practice, the frames 19, 19 upon the sections 17 and 18 are swung to open position and the outside sheets of the selection to be played placed upon the sections 17 and 18 respectively. The sections 19, 19 are now swung upon the outside sheets of the composition, while the sections 20 and 21 are open and the center page of the com-

position to be played placed between the frames 20 and 21 and the latter closed. Suitable holding devices 22 are carried by certain edges of the respective frames to hold such frames in closed position so as to prevent accidental detachment of the sheets of music therefrom.

The center frames 20 and 21 are preferably equipped with finger tabs 24 whereby such central frames, when holding the sheet of music, may be swung from one side to the other during the playing of the composition.

In practice, the rod 2 is secured to the upper surface of the piano and the rods 10 and 13 arranged in the desired positions and locked in such positions, while the sheets of music are placed within the sheet holder 16 as previously described. While the selection is being played the central frame carrying the middle sheet of music may be swung from one position to another by the finger tabs so that the performer may follow the music.

The rod 13 is preferably equipped with oppositely projecting arms 25 that support the outer cover sections 17 and 18 respectively of the sheet holder.

While I have herein shown and described one preferred form of my invention by way of illustration, I wish it to be understood that I do not limit or confine myself to

the precise details of construction herein described and delineated, as modification and variation may be made within the scope of the claim and without departing from the 35 spirit of the invention.

I claim:

A sheet music holder comprising outside covers placed edge to edge and pivoted at their meeting edges for swinging movement, 40 frames on the inner surfaces of said covers respectively adapted to hold the outside sheets of a musical composition upon said outside covers and having the outer edges thereof pivoted to the outer edges of said covers, a 45 frame hinged to the inner edge of one of the first-mentioned frames and capable of swinging movement, a frame coöperating with the last-mentioned frame to hold the central sheet of a musical composition and having 50 the outer edge thereof pivoted to the outer edge of the last-named frame, and means for holding the first-mentioned frames in engagement with the respective covers and the last-mentioned frames connected to each 55 other.

In testimony whereof I affix my signature in presence of two witnesses,

R. S. SIMHAN.
